United States Patent Office.

ROBERT MORRIS, OF SALEM, INDIANA.

Letters Patent No. 96,603, dated November 9, 1869.

IMPROVEMENT IN HARVESTERS.

The Schedule referred to in these Letters Patent and making part of the same.

To all whom it may concern:

Be it known that I, ROBERT MORRIS, of Salem, in the county of Washington, and State of Indiana, have invented a new and useful Improvement in Reaping-Machines; and I do hereby declare that the following is a full, clear, and exact description thereof, which will enable others skilled in the art to make and use the same, reference being had to the accompanying drawings, forming part of this specification.

This invention relates to improvements in reaping-machines; and

It consists in the combination and arrangement of certain parts, as hereinafter specified.

Figure 1 represents a plan view of my improved machine.

Figure 2 represents a front view of the same, sectioned on the line $x x o$ fig. 1.

Similar letters of reference indicate corresponding parts.

For driving the crank-shaft A, and to obtain a quick motion, without intermediate gears, I make the driving-wheel B smaller than the other, and place it on a fixed stud, C, below the axial line of the shaft D, which I prefer to arrange in a fixed position.

If preferred, the shaft D and stud C may be made in one piece, and bent immediately inside of the wheel B, as required for the different axial lines.

On the shaft D, I provide a bevel-wheel, E, gearing with the pinion of the crank-shaft, and having a toothed hub, F, gearing with an internally-toothed rim, G, projecting from the side of the wheel B.

The toothed hub is thereby set into motion by the rim of the driving-wheel, and being smaller than the said rim, its motion is considerably accelerated, so that the requisite speed of the cutter-bar is readily obtained.

For raking and delivering the grain, I provide the endless belts H, inclined continuation I of the apron, weighted tilting-shelf K, hood L, and guard-fingers M.

The inclined continuation I of the apron is supported, in any suitable way, on a rear extension of the frame, and the belts are operated by a driving-roller, N, at the top of the said part I, which roller may be operated by a belt, O, and intermediate shaft P, deriving motion from the wheel Q.

The said belts work under a guide-roller, R, in the angle of the apron, and the extension thereof, and over guide-rollers S T.

The roller R has yielding supports.

They, i. e., the belts, deliver the grain from the top roller N to a swinging shelf, K, at the side of the machine, under the hood L. This shelf is pivoted at W, and is provided with a weighted arm, X, which, when

overbalanced by the weight of the grain, rises, and allows the grain to be discharged on the ground. When discharged, the weight brings the shelf back again.

To prevent the delivery and consequent scattering of the grain while the discharging is taking place, a set of guard-fingers, M, is provided on an oscillating shaft, connected by a rod to the arm of the tilting-lever, and so adjusted, that when the shelf tilts down, the said fingers will swing into the path of the falling grain, through holes provided in the hood, and arrest the grain until the shelf moves back, when the said fingers will be withdrawn, and the withdrawal will discharge the grain thereon to the shelf K.

The weight on the tilting-apron K may be adjusted to discharge gavels of any given weight, and a dial and pointer may be connected to the said tilting-shelf, so as to take a record of the number of gavels delivered.

The apron is suspended on pivot-joints from the frame of the machine, so as not to require a supporting-wheel at the outer end, as commonly employed, and which commonly run in the standing grain, to such an extent as to injure the grain, and also creating an undue amount of side draught. For supporting the apron in this way, the bottom board Y thereof projects sufficiently under the frame of the rear extension to maintain the said apron in the horizontal plane. If preferred, the side rails of the said apron may also be similarly arranged. Other arrangements may be employed.

The reel Z is so connected to its supports that it may be readily detached; and when it is detached, the apron may be turned up over the inclined extension I, for transportation from place to place.

By placing the axis of the driving-wheel B before or behind the axle D, or in any other direction therefrom, the same results may be obtained, except, that by reducing the diameter of the wheel B, the motion is increased.

Having thus described my invention,

I claim as new, and desire to secure by Letters Patent—

1. The driving-wheel, B, toothed rim G, wheel E, with toothed hub F, shaft D, and crank-shaft A, all combined and arranged substantially as specified.

2. The combination of the tilter K and weighted arm X with a hood, L, and guard M, all constructed and arranged as and for the purpose specified.

ROBERT MORRIS.
